UNITED STATES PATENT OFFICE.

HORATIO ALLEN, OF NEW YORK, N. Y.

CUT-OFF-VALVE GEAR OF STEAM-ENGINES.

Specification of Letters Patent No. 18,837, dated December 15, 1857.

To all whom it may concern:

Be it known that I, HORATIO ALLEN, of the city, county, and State of New York, have invented an Improvement in Cut-Off- 5 Valve Gear of Steam-Engines, of which the following is a full, clear, and exact specification.

The improvements described herein, are 10 improvements on the cut-off combinations, patented by Horatio Allen, February 6th, 1849; and Samuel H. Gilman, December 10th, 1850. By reference to the specification and drawings of those patents, it will be seen that the steam valve is raised by 15 means of a loose toe, and returned to its seat by lowering, or by tripping the loose toe.

It is the object of the present improvement to provide a control of the fall of the 20 toe, after it is tripped; this is effected by connecting with the end of the toe, a piston or plunger operating in a chamber containing water or other fluid, the outlet of the fluid from the chamber being of such area 25 as will provide an adequate controlling resistance.

The drawings herewith represent the combination.

A, is the shaft which carries the loose toe; 30 it may be an independent shaft or the rock shaft which carries the exhaust toe. See Figures 1 and 2.

B, is the loose toe by which the lifter C is raised.

D, is a reservoir in which is placed the 35 controlling chamber E. In this chamber operates the plunger F. This plunger is connected with the end of the toe B by the rod G.

H, is a valve opening into the controlling 40 chamber, and I, is an outlet from the controlling chamber, the area of which can be adjusted by the stop valve K.

The operation of this combination is as 45 follows: The reservoir D, is nearly filled with water, oil, or other fluid. When the toe is raised, it lifts the plunger and the vacuum thus produced in the controlling chamber is filled from the reservoir through the valve 50 H. When the toe is tripped, the fall of the toe carries down the plunger, the valve H closes, and the fluid can only escape by the outlet I. As the toe falls, the leverage with

which the pressure on the toe acts to force the fluid through the outlet becomes of less 55 and less length, and as the toe reaches a position just before the steam valve is seated, the leverage becomes very small, and the motion of the toe is controlled by the diminished power to force the fluid through 60 the outlet. The toe may be raised and tripped in various ways. In the one represented, an arm L fastened on the rock shaft, carries the pin M, on which the pawl N drops into gear by suitable notch. When the pawl 65 is thrown out of gear, the toe is tripped and falls as fast as the controlling plunger will permit.

The controlling chamber could be provided with a supply valve and outlet in 70 other ways than that represented, without changing its mode of operation. A very compact arrangement is one where a piston is used; the supply valve is in the bottom of the piston, and the outlet is through the center of the valve. In this form no reservoir is required, the chamber forming the reservoir and the fluid passing alternately from above to below the piston and from below to above the piston. 80

The toe could be controlled just as it reached the position of seating the valve by substituting for the plunger and controlling chamber the dash pot with secondary chamber, the parts being so adjusted that the resistance created by the secondary chamber should come into action at the proper time. 85

I do not claim the use of a controlling chamber or dash pot to break the fall of the valve as they have long been used in 90 connection with valve gear; but

I claim—

As an improvement on the cut-off valve gear patented by Horatio Allen, February 9th, 1849, and by Samuel H. Gilman, December 10th, 1850, the combination of a plunger operating to force a fluid through an orifice or of the dash pot with secondary chamber, with the loose toe whereby the fall of the toe when tripped is controlled, substantially 100 in the manner and for the purpose set forth.

HORATIO ALLEN.
